UNITED STATES PATENT OFFICE.

EINAR P. EKMAN, OF CHICAGO, ILLINOIS.

DESIGN FOR AN AUTOMOBILE-RADIATOR ORNAMENT.

55,259.

Specification for Design.

Patented May 25, 1920.

Application filed August 17, 1918. Serial No. 250,405. Term of patent $3\frac{1}{2}$ years.

To all whom it may concern:

Be it known that I, EINAR P. EKMAN, a citizen of the Kingdom of Sweden, and residing at Chicago, in the county of Cook and State of Illinois, have invented a new, original, and ornamental Design for an Automobile-Radiator Ornament, of which the following is a specification, reference being had to the accompanying drawing, which forms a part of my specification, and in which—

The figure is a perspective view of my improved device, showing the side thereof, which comprises a shaft or rod adapted to be secured to the radiator-cap of an automobile; the rod being of substantial length,

and a liberty cap disposed substantially centrally on the upper end of the rod and formed integral therewith; the liberty cap being tilted slightly upwardly at its front in the usual manner in which such caps are worn; while the rod is adapted to receive a small flag or pennant which may be secured thereto in any suitable manner.

I claim:—

The ornamental design for an automobile radiator ornament, as shown.

EINAR P. EKMAN.
